(57) **CLAIM**

The ornamental design for a mobile device power bank with accessory ports, as shown and described.

DESCRIPTION

FIG. 1 is a front perspective view of a mobile device power bank with accessory ports, according to an embodiment; FIG. 2 is a front view of the mobile device power bank with accessory ports illustrated in FIG. 1; FIG. 3 is a rear view of the mobile device power bank with accessory ports illustrated in FIG. 1; FIG. 4 is a left side view of the mobile device power bank with accessory ports illustrated in FIG. 1; FIG. 5 is a right side view of the mobile device power bank with accessory ports illustrated in FIG. 1; FIG. 6 is a top view of the mobile device power bank with accessory ports illustrated in FIG. 1; and, FIG. 7 is a bottom view of the mobile device power bank with accessory ports illustrated in FIG. 1. The broken lines are for illustrating portions of the mobile device power bank with accessory ports that form no part of the claimed design.
